UNITED STATES PATENT OFFICE

GEORGE W. WALLACE, OF SAN FRANCISCO, CALIFORNIA, ASSIGNOR TO THE S. E. COMPANY, A CORPORATION OF DELAWARE

CARBONIZING APPARATUS

Application filed March 15, 1927. Serial No. 175,599.

This invention relates to carbonizing apparatus; and it comprises an apparatus of the shaft kiln type for producing oil from shale, carbonizing coal, etc., having a vertical shaft adapted to be charged through an opening in its top and provided with an inclined bottom, together with a power operated door for closing an opening in the side wall of the carbonizing chamber adjacent its inclined bottom and at an acute angle thereto, the said door being formed with a grate in communication with the interior of the carbonizing chamber and a chamber exterior of said grate, the said chamber having an inclined bottom serving for discharging spent shale from the chamber and for conveying liquids draining downward to a discharge pipe; said invention further contemplating the provision of a separable connection between the discharge pipe and the chamber of said door whereby, when the door is in position to cover the opening in the wall of the carbonizing chamber, a liquid and gas-tight connection is effected between the chamber and discharge pipe to prevent leakage; all as more fully hereinafter set forth and as claimed.

In various methods of producing oil from shale, low temperature carbonization of coal and the like, operation is on successive charges or batches of material, carbonized one after another in a down shaft vertical kiln. In apparatus of this type it is a desideratum to be able to remove a spent charge of material quickly and completely and be in a position to take care of another charge. The present invention is intended to provide for quick removal of spent charges and it includes certain structures at the bottom of a carbonizing shaft and intended to permit not only quick removal of spent solids after carbonization but of tars and liquids during carbonization. By using a vertical shaft with a sharply inclined bottom and a power operated side door, discharge of spent material becomes quick and ready. And by provision of suitable means at the vertex of the acute angle formed by door and bottom, collection of down-draining liquid, becomes positive. While not limited thereto the present invention is particularly applicable to

apparatus of the types of those used in carrying out the processes described and claimed in my prior Patent No. 1,536,696 of May 5, 1925. In the present invention a vertical shaft is provided with an inclined bottom and with means for dumping a charge opening into the side of the shaft near the bottom and having a power operated door. This door is formed with a grate and with chamber space for collecting liquids, the collected liquids being delivered to a discharge main through a separable connection broken when the door is raised but otherwise sealed against escape of gas and liquids. With the door in place down-draining liquids (oils and tars) go to the vertex of the acute angle formed by door and bottom; and are thence removed.

In the accompanying illustration I have shown, more or less diagrammatically, certain embodiments of the present invention. In this showing,

Fig. 1 is a front elevation of a series of carbonizing chambers showing the doors in raised and lowered positions, and operating either by hydraulic pressure or by compressed air;

Fig. 2 is an end view, partly in section, showing a battery of carbonizing chambers the bottoms of which are inclined downwardly toward each other; this being for the purpose of dumping exhausted charges of material treated into cars or other means for its disposal;

Fig. 3 is a sectional view, on an enlarged scale, taken along line 3—3 of Fig. 1;

Fig. 4 is a similar sectional view, taken along line 4—4 of Fig. 1;

Fig. 5 is a detail view of the bottom of a carbonizing chamber taken in vertical section and showing a modified structure where in the grate and vapor chamber are located in the inclined bottom of the carbonizing chamber instead of in the sliding door;

Fig. 6 is a detail view of a modified form of gas-tight connection between the vapor chamber and discharge pipe; and,

Fig. 7 is a side view, partially in elevation and partially in cross section, illustrating means for recovering heat energy from waste shale.

As shown, each of the carbonizing chambers 1 is a vertical or upright shaft and is lined with fire brick or other refractory material 2. It may be either circular in cross-section or square with rounded corners as shown in Fig. 3.

Each carbonizing chamber has an inclined bottom 3 and an opening 4 in its side wall for the removal of spent charges. Each opening 10 is closed by a vertically sliding door 5, mounted exteriorly of the carbonizing chamber 1 and guided in its movement by flanges 6. The door is composed of a grate 7, presented to the interior of the carbonizing chamber, 15 and a vapor chamber 8 exterior of the grate to receive vapors and liquids condensed during the process. From 8, these are delivered to a discharge pipe 9 and go to main 10. The bottoms of the vapor chambers and connecting 20 parts are inclined downwardly to permit gravity flow to main 10.

Pipe connection 12 projects from the lower part of the vapor chamber 8 and carries at its end flange 13. The face of the flange 13 is beveled, as is also the face of a corresponding flange 14 on pipe 9, connecting therewith, this providing a cam surface so that when the pipe 12 is brought into alignment with pipe 9 on closing of door 5, the action of the complementary cam faces forms a tight joint and an efficient seal against escape of gases and liquids.

A modification of this gas-tight joint is shown in Fig. 6 wherein pipe 20 communicating with the vapor chamber 21 in the sliding door, is formed with a flange 22 which, when the door is in closed position, abuts a similar flange 23 formed on the end of discharge pipe 24. During the operation of the 40 carbonizing chamber the flanges 22 and 23 are coupled together by a split clamp 25. A valve 26 in pipe 24 controls the flow of vapors and condensate as in the other embodiment of my invention.

45 The doors 5 can be operated by any suitable power means. As here shown, hydraulic power is used. Water under pressure is admitted to a cylinder 15. By manipulating valve 16 the water is admitted through ports 50 17 or 18 to raise or lower the door. Any other desirable power means, such as compressed air or electricity, may be used.

As shown in Fig. 5 the combined grate and vapor chamber 5^a is mounted in the inclined 55 floor 3 of the carbonizing chamber, thus dispensing with the necessity of placing it in the slideable door 19. This construction is particularly adapted for use where the materials treated form either clinker or coke when heated.

The carbonizing chambers shown may be operated in various ways, the charge-removing means illustrated being useful whatever the process used in carbonizing. Generally 65 however the carbonizing chamber operates

upon successive charges or batches of shale or coal. In the usual operation the carbonizing chamber is filled and combustion instituted by air and gas admitted through ports 30 and 31 (see Fig. 2). Reference may here be made to the prior patents to Dundas and Howes No. 1,469,628 and Wallace 1,536,696. In operation, the charge is heated at the top until a more or less exothermic carbonizing reaction is instituted and carbonization is thereafter propagated downwardly as a traveling zone, the progress of the zone being regulated by control of the draft currents admitted at 30 and 31. In aiding this control and to secure certain other results, either the air or the gas, or both, may be diluted with steam or products of combustion. These act as endothermic agents and have certain other results. As the traveling zone of carbonization goes downward the gases and vapors formed flow downward ahead of it into and through the relatively cooler material, pre-heating this material. As their flow is away from the hot zone, secondary decomposition can be avoided to as great an extent as may be desired.

After the shale, or coal, or whatever may be treated in the apparatus, has been completely carbonized it is necessary to remove the spent material. This spent material may be ash or carbon according to the material operated upon, the apparatus being applicable to carbonizing coal, peat and wood, to make carbonaceous fuel as well as to the extraction of oil from shale. When the carbonizing operation is complete residue remaining in the carbonizing chamber is discharged by raising the door 5. An advantageous arrangement of the carbonizing chambers is shown in Fig. 2. In this showing, a continuation of the inclined bottom of the retort directs the waste down into a car, shown in dotted lines, while steam or water is used for quenching.

In the case of oil shale, the spent residue often contains sufficient carbon to warrant utilizing its combustible energy. It may be burned to generate heat which is utilized in conjunction with the operation of the apparatus. In Fig. 7 is shown means for utilizing the heating value of the hot residue. It comprises a traveling grate 21 positioned on suitable supporting elements 22 disposed between the carbonizing chambers 1 and below the inclined bottoms 3. The discharge pit defined between the carbonizing chambers is covered with an arched roof 23 which serves to prevent loss of heat and hot gases.

A fan, stack, or similar means, indicated by the reference numeral 24, is employed to create a draft which draws the hot gases from the discharged shale to a waste heat boiler, or other suitable means, for utilizing the energy thus collected. Air may be introduced to the hot discharged material to burn

carbon therein, thereby generating an additional amount of heat, which is utilized in the manner indicated. The waste material may be removed continuously by operation of the continuously moving grate conveyor. This construction possesses not only the advantage of conserving energy that otherwise would be lost, but it eliminates the liberation of smoke and dust.

10. What I claim is:

1. Carbonizing apparatus for treating shale and the like which comprises a vertical shaft kiln having vertical side walls, an inclined bottom extending therebetween, one side wall being formed with an opening adjacent the lowermost point of said bottom, a door slidably mounted to cover and uncover said opening, said door comprising a grate presented to the interior of said chamber and a vapor collecting compartment exterior thereof, and means, operable when the door is in position to cover the opening directly communicating with said compartment for conducting liquids and vapors therefrom to a point below said compartment and exterior the vertical shaft kiln.

2. Carbonizing apparatus for treating shale and the like which comprises an upright closed chamber having opposed vertical side walls, a removable closure in one side wall of said chamber adjacent the bottom thereof, said closure consisting of an oil receptacle having a lateral outlet and a grate covering said receptacle, and means for moving said closure to a position for discharging the contents of said chamber, the edge of the closure being adapted to make a tight fit against the bottom wall of the chamber.

3. Carbonizing apparatus for treating shale and the like comprising a top-fired shaft having vertical side walls, a door in one of the side walls adjacent a low point thereof and an inclined bottom at an acute angle to said door and low point in said side wall, and means for collecting and removing liquids draining down to the vertex of said angle, said means comprising a chamber within the door.

In testimony whereof, I have hereunto affixed my signature.

GEORGE W. WALLACE.
